CLAIM

The ornamental design for a piano-like structure for aerial performance, substantially as shown and described.

DESCRIPTION

FIG. 1 is an isometric view of a piano like structure for aerial performance;

FIG. 2 is a front view of the structure of FIG. 1.

FIG. 3 is a rear view of the structure of FIG. 1.

FIG. 4 is a left side view of the structure of FIG. 1.

FIG. 5 is a right side view of the structure of FIG. 1.

FIG. 6 is a top view of the structure of FIG. 1.

FIG. 7 is a bottom view of the structure of FIG. 1; and,
FIG. 8 is an isometric view of the structure of FIG. 1 in operation.

The dashed lines in the drawings form no part of the claimed invention.
